UNITED STATES PATENT OFFICE.

CHESTER W. HARTSHORN, OF FORD, KANSAS.

CARBURETER.

1,198,029.

Specification of Letters Patent. Patented Sept. 12, 1916.

Application filed March 18, 1915. Serial No. 14,847.

To all whom it may concern:

Be it known that I, CHESTER W. HARTSHORN, a citizen of the United States, residing at Ford, in the county of Ford and State 5 of Kansas, have invented a certain new and useful Improvement in Carbureters, of which the following is a specification.

My invention relates to improvements in carbureters.

10 One of the objects of my invention is to provide a carbureter with novel means for obtaining a thorough mixture of air and fuel, which will have a maximum of efficiency, which is simple in construction 15 and not liable to get out of order, and in which the parts may be quickly assembled and disassembled.

A further object of my invention is to provide novel means for heating the charges.

20 Still another object of my invention is to provide novel means by which the relative proportions of air and fuel may be varied while the engine is running.

Other novel features of my invention are 25 hereinafter fully described and claimed.

In the accompanying drawings, which illustrate the preferred embodiment of my invention, Figure 1 is a central vertical sectional view of my carbureter. Fig. 2 is a 30 plan view of the same, partly broken away. Fig. 3 is a side elevation of a part of the device, showing the operating lever and some of the parts connected thereto. Fig. 4 is a horizontal section on the line 4—4 of Fig. 1. Fig. 5 is a side elevation of the upper part of my improved carbureter. Fig. 6 is a horizontal sectional view, partly 35 broken away and enlarged, showing the butterfly valve and connected parts in the closed position. Fig. 7 is an enlarged sectional view on the line 7—7 of Fig. 5. Fig. 8 is a horizontal section on the line 8—8 of Fig. 1.

Similar reference characters designate 45 similar parts in the different views.

The carbureter casing comprises, preferably an upper part 1, and a lower part 2 connected by a vertical bolt 3 with the upper part, an annular heating chamber 4 being 50 held clamped between said upper and lower parts.

Fuel, such as gasolene, is supplied from a suitable source of supply by a pipe 5 which communicates with an inlet 6 of a settling chamber 7 in the upper part of the casing. 55 The part 1 is provided with a screw thread.

ed hole communicating with the chamber 7 and having removably fitted therein a screw plug 8 having in its lower end a recess 9 which communicates with lateral holes 10 in the plug 8, the periphery of which is provided with an annular groove 11 communicating with the holes 10 and with a passage 12 which extends through a vertical tubular depending projection 13, which projects into a float chamber 14 in the lower part 2.

The float chamber is provided near its bottom with an outlet 15 which communicates with a vertical fuel pipe 16, the lower end of which is normally closed by a threaded plug 17, and the upper end of which is provided with a discharge hole 18 adapted to be closed by a valve 19 having a stem which extends above and below said hole 18. A coil spring 20 encircling the lower part of said stem, bears at its upper end against a transverse pin 21 in said stem, and at its lower end the spring bears upon the plug 17. The spring 20 normally forces 30 the valve 19 to the closed position.

An annular float 22 encircles the projection 13 and carries a vertically adjustable screw valve 23 which is slidably mounted in a cap 24 secured to the lower end of the 35 projection 13, the lower end of which is provided with a valve seat 25 in which is adapted to be seated the valve 23 when the float 22 rises to a predetermined position.

Fuel passing through the inlet 6 enters 40 the settling chamber 7 and passes upwardly therefrom through a screen 26 which extends across the chamber above the inlet 6. The fuel passes through the recess 9, holes 10, groove 11, passage 12, and seat 25 into 45 the cap 24, from which the fuel passes by openings 27 in the cap into the central opening of the float 22, passing from thence into the float chamber 14 from which it passes by the outlet 15 into the fuel pipe 16. When 50 the valve 19 is open the fuel passes out of the fuel pipe 16, by the discharge opening or hole 18, into an air tube 28 which is concentric with and spaced apart from the fuel pipe 16, and which has a lower open 55 end communicating with the atmosphere through an air inlet 29 provided in the lower part of the part 2 of the casing.

The upper end of the air tube 28 is provided with a central air inlet, preferably 60 comprising a vertical tube 30, which extends centrally through the central opening of the

heating chamber 4 and through a mixing chamber 31, provided in the upper part 1 of the casing, and having its upper end communicating with the atmosphere.

5 The central opening, designated by 32, of the heating chamber 4 communicates with an inlet 33, in the lower part of the mixing chamber 31.

10 A valve 34, slidably mounted on the tube 30 is normally held by a coil spring 35 in a position closing the opening 32 and inlet 33.

15 For varying the pressure of the spring 35 upon the valve 34, there is slidably mounted on the tube 30 a plate 36 having a vertical screw-threaded hole in which is rotatably fitted a screw 37, which extends through and is rotatably mounted in a vertical hole provided in the upper part 1 of the casing. A collar 38 secured to the screw

20 37 within the mixing chamber 31 is adapted to contact with the casing to limit the vertical movement upwardly of the screw 37, the head of which bears against a spring washer 37' which rests upon the top of the 25 casing 1. By turning the screw 37, the plate 36 may be vertically adjusted to change the pressure of the spring 35 on the valve 34.

25 A series of discharge tubes 39 have their lower ends connected to the air tube 28 concentrically with respect to the tube 30 and fuel pipe 16, the inlet ends of said discharge tubes being disposed adjacent to the lower end of the tube 30 and the upper end of the pipe 16. The discharge tubes 39 extend upwardly through the annular heating chamber 4 and have their upper ends disposed concentrically around and adjacent to the inlet 33 and valve 34 and discharging into the mixing chamber 31.

40 The mixing chamber 31 is provided with an outlet 40 which is adapted to be connected to the cylinder of an explosive engine and through which the mixed air and fuel vapor passes to the engine. The passage of fluid through the outlet 40 is controlled by means of a butterfly valve 41, which is rigidly secured to a horizontal rock shaft 42 which extends through the side walls of the casing part 1 and which has 45 secured to it, Fig. 3, a lever 43 which serves as an operating lever and which has connected to it, Fig. 5, a rod 44, by means of which the lever may be swung. When the butterfly valve 41 is swung to the open position

50 and the engine is started, a partial vacuum will be produced in the mixing chamber 31, thereby effecting a suction in the discharge tubes 39 and in the air tube 28. If now the valve 19 be opened, the liquid fuel would 55 be drawn from the fuel pipe 16 through the discharge hole 18 and into the air tube 28. At the same time air will be drawn upwardly through the inlet 29 and downwardly through the tube 30 into the air tube 60 28. As the discharge opening 18 is adja-

cent to and in alignment with the tube 30 and is adjacent to the inlet ends of the discharge tubes 39, the incoming fuel will mix with the air coming through the lower end of the air tube 28 and through the tube 30 70 and will be carried therewith laterally to the discharge tubes 39 through which the mixture will pass into the mixing chamber 31, from which it will escape past the valve 41 through the outlet 40 to the engine, not 75 shown. As the discharge tubes 39 extend through the heating chamber 4, these tubes will be heated, thereby heating the explosive mixture passing through said tubes.

80 Any suitable means may be employed for heating the chamber 4, as by the exhaust from an explosive engine passing into the chamber 4 by means of an exhaust pipe 45, Fig. 5.

85 For depressing and thereby opening the fuel valve 19 synchronously with the opening of the butterfly valve 41, the following described mechanism is provided: Referring particularly to Figs. 5, 6 and 7, 46 designates a crank which is secured to the rock shaft 42 and which is provided with a lug 47 to which is pivoted by a transverse pin 48 an arcuate member comprising preferably an annulus 49 upon the periphery of which is adapted to bear a member 50 which is pivoted to a horizontal rock shaft 51 which is oscillatably mounted in a bearing 52 provided on the upper side of the upper part 1 of the casing. Secured rigidly to the rock shaft 51 is a crank 53 provided with a transverse hole which is screw-threaded and has fitted therein an adjusting screw 54, which is adapted to bear against the member 50, as shown in Figs. 1, 2 and 5. Rigidly secured to the rock shaft 51 is a crank 55 105 which has its outer end mounted in a transverse slot 56 provided in the upper part of the stem of the valve 19, Figs. 1 and 7. By adjusting the screw 54, the crank 53 and arm 50 may be swung so as to vertically adjust the outer end of the member 50 to compensate for wear of the valve 19 in its seat and for the wear on the periphery of the member 49 or lower side of the member 50. By adjusting the screw 54, the valve 19 may 110 be normally retained slightly open for cranking and slow speed purposes. The arcuate member 49, the function of which is to lift the member 50 so as to depress and open the valve 19, is preferably adjustable to different degrees of eccentricity with respect to the rock shaft 42, which it encircles. The distances from the center of the rock shaft 42 and from the center of the arcuate member 49 to the center of the pin 48 are 115 substantially the same, so that it is possible to swing the member 49 to a position in which the center of the member 49 and that of the shaft 42 will coincide, at which time there would be no eccentricity of the pe- 120

125

riphery of the member 49, and the swinging of the lever 43 would not cause any lifting of the member 50. To obtain, therefore, the desired lift of the member 50 for depressing 5 and opening the valve 19, the amount required to secure the desired mixture of fuel and air, means are provided for swinging the member 49 toward and from the neutral position. To effect this, the crank 46 is provided 10 with a screw-threaded hole in which is fitted an adjusting screw 57, Fig. 5, which is disposed radially to the shaft 42, and which bears at its inner end against the periphery of the member 49 below the pivot pin 48. By 15 adjusting the screw 57 inwardly, said screw will swing the member 49 so as to increase its eccentricity with respect to the rock shaft 42. A spring 58 secured to the crank 46 and bearing against the head of the screw 20 57 releasably retains said screw in the position to which it is adjusted. A coil spring 59 having its ends secured respectively to lugs 60 and 61 which are provided respectively on the crank 46 and member 49, normally holds the latter member against the inner end of the screw 57.

The lower end of the float chamber 14 is provided with a screw-threaded hole 62, which is in alinement with the valve 23 and 30 which has removably fitted in it a shut-off cock 63.

In the operation of my invention, the operating lever 43 is swung from the closed position, in which a projection 64 on the lever 43 is in contact with a lug 65 on the upper part 1 of the casing, Figs. 2 and 3, and in which the crank 46 and screw 57 are in the position shown in Fig. 6, thereby rocking the shaft 42 so as to swing the 40 arcuate member 49, thereby lifting the member 50 and opening the valve 19 by the mechanism already described. If the engine is now cranked so as to create a suction in the mixing chamber 31, fuel will be drawn 45 from the fuel pipe 16 into the air tube 28, there mixed with air entering said tube through the tube 30 and inlet 29 and then discharged through the tubes 39 into the mixing chamber 31. As the speed of the 50 engine increases, and the richness of the mixture in the chamber 31 requires to be reduced by an increased supply of air, the valve 34 will be lifted against the pressure of the spring 35 and air will be drawn into the mixing chamber 31 through the opening 32 and inlet 33, which are in communication with an air inlet 66 which communicates with the atmosphere and which encircles the air tube 28, see Fig. 1. The air thus drawn through the opening 32 will be heated by the heating chamber 4 as is the mixture which passes through the tubes 39.

By having the tubes 39 disposed with their discharge ends adjacent to and concentric with the inlet 33, a thorough mixture

of the air passing through the opening 32 and with the mixed air and vapor passing through the tubes 39 will be effected. By reason of the mechanism connecting the butterfly valve 41 and the fuel valve 19, the latter will be opened an amount proportionate to the opening of the valve 41. The opening movement of the latter may be limited by means of an adjusting screw 67 which is mounted in the lever 43 and is 70 adapted to strike against the lug 65, Figs. 2 and 3. By adjusting the screw 37 so as to vary the pressure of the spring 35, the degree of suction required to lift the valve 34 may be varied to suit the atmospheric 75 conditions and the quality of liquid fuel 80 employed.

As the liquid fuel enters the float chamber 14, the valve 19 being closed, the liquid will rise in the float chamber, thus lifting 85 the float 22 until the valve 23 closes the lower end of the passage 12, at which time, if the valve 23 is in the proper adjustment, the level of the liquid in the float chamber 14 will be slightly below the top of the fuel 90 pipe 16, as, for example, at about the plane of the line a—b in Fig. 1. By adjusting the screw 23, the rise of the float 22 may be adjustably limited, thus permitting a variation in the level of the liquid in the float chamber 95 14.

By removing the plug 8 and screen 26, the sediment which collects in the settling chamber 7 may be accessible for its removal.

I do not limit my invention to the structure shown and described, as modifications, within the scope of the appended claims, may be made without departing from the spirit of my invention.

What I claim is:—

1. In a carbureter, a mixing chamber, an air tube having an air inlet, a series of discharge tubes connected to said air tube concentrically with and adjacent to said inlet and discharging into said mixing chamber, 110 and a fuel pipe discharging into said air tube adjacent to and in alinement with and in a direction opposite to the passage of air from said inlet and adjacent to the inlet ends of said discharge tubes. 115

2. In a carbureter, a mixing chamber having an air inlet, an air tube having an air inlet, a series of discharge tubes connected to said air tube concentrically with and adjacent to the air inlet of said air tube and 120 discharging into said mixing chamber concentrically with and adjacent to said air inlet of said mixing chamber, and a fuel pipe discharging into said air tube adjacent to and in alinement with and in a direction 125 opposite to the passage of air from the air inlet of said air tube and adjacent to the inlet ends of said discharge tubes.

3. In a carbureter, a mixing chamber having an air inlet, an air tube having an air 130

- inlet, a series of discharge tubes connected to said air tube concentrically with and adjacent to the air inlet of said air tube and discharging into said mixing chamber concentrically with and adjacent to said air inlet of the mixing chamber, a fuel pipe discharging into said air tube adjacent to and in alinement with the air inlet of said air tube and adjacent to the inlet ends of said discharge tubes, and an annular heating chamber through which said discharge tubes extend and the central opening of which communicates with the atmosphere and with the air inlet of said mixing chamber.
4. In a carbureter, a mixing chamber having an air inlet, an air tube having an air inlet, a series of discharge tubes connected to said air tube concentrically with and adjacent to the air inlet of said air tube and discharging into the mixing chamber concentrically with and adjacent to said air inlet of the mixing chamber, a fuel pipe discharging into said air tube adjacent to and in alinement with and in a direction opposite to the passage of air from the air inlet of said air tube and adjacent to the inlet ends of said discharge tubes, and an inwardly opening normally closed valve controlling the air inlet of the mixing chamber.
5. In a carbureter, a mixing chamber, an air tube having an air inlet, a series of discharge tubes connected to said air tube concentrically with and adjacent to said inlet and discharging into the mixing chamber, a fuel pipe discharging into said air tube adjacent to and in alinement with said air inlet and adjacent to the inlet ends of said discharge tubes, an annular heating chamber through which said discharge tubes extend and having a central opening communicating with the atmosphere and with said mixing chamber, and an inwardly opening valve normally closing said central opening.
6. In a carbureter, a mixing chamber, an air tube having one end communicating with the atmosphere, a series of discharge tubes connected concentrically with said air tube and discharging into said mixing chamber, a fuel pipe disposed concentrically in said air tube and spaced apart therefrom and discharging therein adjacent to the inlet ends of said discharge tubes, and an annular heating chamber through which the discharge tubes extend and provided with a central opening communicating with the atmosphere and with said mixing chamber.
7. In a carbureter, a mixing chamber, an air tube having one end communicating with the atmosphere, a series of discharge tubes connected concentrically with said air tube and discharging into said mixing chamber, a fuel pipe disposed concentrically in and spaced apart from said air tube and discharging therein adjacent to the inlet ends of said discharge tubes, and an annular heating chamber through which said discharge tubes extend and having a central opening communicating with the atmosphere and with said mixing chamber.
8. In a carbureter, a mixing chamber, an air tube having one end communicating with the atmosphere and provided at the other end with an air inlet, a series of discharge tubes connected to said air tube concentrically with and adjacent to said inlet and discharging into the mixing chamber, and a fuel pipe disposed concentrically in said air tube and spaced apart therefrom and discharging therein adjacent to and in alinement with said air inlet and adjacent to the inlet ends of said discharge tubes.
9. In a carbureter, a mixing chamber having an air inlet, an air tube having one end communicating with the atmosphere and having an air inlet at its other end, a series of discharge tubes connected to said air tube concentrically with and adjacent to the air inlet of said air tube and discharging into said mixing chamber adjacent to the air inlet thereof, and a fuel pipe disposed concentrically in said air tube and spaced apart therefrom and discharging therein adjacent to and in alinement with the air inlet of said air tube and adjacent to the inlet ends of said discharge tubes.
10. In a carbureter, a mixing chamber having an air inlet, an air tube having one end communicating with the atmosphere and having an air inlet at the other end, a series of discharge tubes connected to said air tube concentrically with and adjacent to the air inlet of said air tube and discharging into the mixing chamber, a fuel pipe disposed concentrically in said air tube and spaced apart therefrom and discharging therein adjacent to and in alinement with the air inlet of said air tube and adjacent to the inlet ends of said discharge tubes.
11. In a carbureter, a mixing chamber, an air tube having one end communicating with the atmosphere and having an air inlet at the other end, a series of discharge tubes connected to said air tube concentrically with and adjacent to said air inlet and discharging into the mixing chamber, a fuel pipe disposed concentrically in and spaced apart from said air tube and discharging therein adjacent to and in alinement with said air inlet and adjacent to the inlet ends of said discharge tubes, and an annular heating chamber through which said discharge tubes extend and having a central opening communicating with the atmosphere and with said mixing chamber.
12. In a carbureter, a mixing chamber,

- an air tube having one end communicating with the atmosphere and having an air inlet at the other end, a series of discharge tubes connected to said air tube concentrically with and adjacent to said air inlet and discharging into said mixing chamber, a fuel pipe disposed concentrically in and spaced apart from said air tube and discharging therein adjacent to and in alignment with said air inlet and adjacent to the inlet ends of said discharge tubes, an annular heating chamber through which said discharge tubes extend and having a central opening communicating with the atmosphere and with said mixing chamber, and an inwardly opening valve normally closing said central opening.
13. In a carbureter, a mixing chamber having an outlet, a fuel valve, a rock shaft, 20 a valve carried by said rock shaft and controlling said outlet, a member carried by said rock shaft and adjustable thereon to different positions, a second rock shaft having a crank, an adjusting screw mounted in said 25 crank, a member pivoted to said second rock
- shaft and adapted to bear against said screw, and to be actuated by said adjustable member, and means operated by said second rock shaft for actuating said fuel valve.
14. In a carbureter, a mixing chamber 30 having an outlet, a fuel valve, a rock shaft, a valve carried by said rock shaft and controlling said outlet, an arcuate member pivoted to said rock shaft, means for adjusting said arcuate member to different degrees of 35 eccentricity relatively to said rock shaft, a second rock shaft having a crank, an adjusting screw carried by said crank, means operated by said second rock shaft for actuating said fuel valve, and a member pivoted 40 to the second rock shaft and adapted to bear against said screw and upon said arcuate member.

In testimony whereof I have signed my name to this specification in presence of two 45 subscribing witnesses.
